UNITED STATES PATENT OFFICE

NICHOLAS LEISTEN, OF DETROIT, MICHIGAN

DESIGN FOR A FINGER RING

Application filed August 3, 1928. Serial No. 27,698. Term of patent 3½ years.

To all whom it may concern:

Be it known that I, NICHOLAS LEISTEN, a citizen of the United States of America, residing at Detroit, in the county of Wayne and State of Michigan, have invented certain new, original, and ornamental Design for Finger Rings, of which the following is a specification, reference being had therein to the accompanying drawings, forming a part thereof, in which—

Figure 1 is a top view of the ring embodying my design; Figures 2 and 3 are, respectively, side and end elevation thereof.

I claim:

The ornamental design for a finger ring, substantially as shown.

NICHOLAS LEISTEN.
